GUIDE TWISTER

William H. Catterall and William J. Barry,
Lebanon, Pa., assignors to Bethlehem Steel
Company, a corporation of Pennsylvania

Application July 29, 1933, Serial No. 682,782

16 Claims. (Cl. 80—53)

This invention relates to an improved device for operating guides in combination with a repeater for rolling mills in which by suitable guiding mechanism the bar is led from the shaping pass of one set of rolls to the shaping pass of another set of rolls. More particularly our invention relates to devices for receiving the end of a bar coming from a roll pass to impart a twist to the bar, and to guide the bar to the entry guide 5 which directs it into another set of pass rolls.

It is well known that in the form of rolling mills where the rolls for successive passes are arranged with their axes in a straight line, it is necessary that the end of the bar be reversed in its direction of travel in order that it may be successively passed through the various passes of the mill. It is also necessary during this reversing operation to give the bar a turn axially before it is passed into the second set of pass rolls. Heretofore this was accomplished by having an operator stand 10 between the roll stands and to grab the end of the bar as it comes from the first pass and by turning his body to turn the end of the bar and direct it into the next pair of rolls. Another method is to provide fixed guides on the delivery 15 side of the mill for twisting the bar as it comes from the first pass and directing it into a repeater which in turn directs the bar into the entry guide of the second pass. The hand turning method is not only difficult and dangerous, but 20 expensive from an operating point of view. The second method of using guides to perform this work has also required the attention of an operator to adjust the entry guides. Twisting guides 25 have been used to twist the bar coming from the first pass, but if the guides remain in a fixed position the twist is communicated to the entry guides of the second set of rolls through the torsion of bar exerted by the twister. This torsional strain is constantly increasing on both the twisting and entry guides as long as the bar is in 30 both and the return loop is increasing in length. This continued torsion greatly increases the wear on the guides and tends to scratch the bar. The 35 tendency of the growing twist in the bar is to push the top roll of the second stand in one direction and the bottom roll in the opposite direction thereby distorting the section and causing excessive end thrust and wear on the roll bearings. 40 By releasing the twister and permitting it to float back to the position of least torsion as the bar enters the second set of rolls, the tendency to scratch the bar is eliminated and prolongs the life 45 of the guides and roll bearings.

An object of this invention is the turning and

controlling of the bar which may be square, diamond shaped, oval, rectangular, or any other shape of cross-section worked through the mill requiring repeaters, so that it will be delivered to the entry guides of the second set of rolls uniformly and in the proper position to receive the shaping and reducing work of the pass in that set of rolls.

Another object is to relieve the torsion on the bar exerted by the twister at the delivery side of 5 the first roll pass.

A further object is to provide for the automatic setting and releasing of the guide twister in combination with apparatus used to operate an opening and closing entry guide on repeating mills, 15 or the setting and releasing of the twister automatically by mechanical means, or by hand, the setting of the twister and the operation of the adjustable entry guides being simultaneous.

The novel features will be more fully understood from the following description and claims 20 taken with the drawings.

Fig. 1 is a plan view of two stands of roll passes, a guide twister at the delivery side of the first stand, a repeater, an adjustable guide at the 25 entry side of the second stand, and electrically controlled means for automatically operating the guide twister and the adjustable guides by the movement of the bar passing between the two stands.

Fig. 2 is an elevation and cross-section taken on lines 2—2 of Fig. 1.

Fig. 3 is a section of the guide twister taken on line 3—3 of Fig. 4.

Fig. 4 is a front view of the guide twister and 35 its housing.

Fig. 5 shows the connection end of a lever for turning the twister.

Fig. 6 is a sectional view through the entry guide taken on line 6—6 of Fig. 1.

Fig. 7 is diagrammatic of the flag switch positioned adjacent the entry guide as shown in Fig. 1.

Referring to the characters of reference on the drawings, the numerals 1 and 2 indicate two 45 stands of rolls of a continuous rod or bar mill, each having a set of rolls 3 and 4 of the two high type. The set of rolls 3 having a reducing pass 5 formed therein while rolls 4 have a pass formed as at 6. From Fig. 2 it will be noted that the 50 bottom roll of stand 1 is in line with the top roll of stand 2 so that the coupling connecting the two stands will move the piece being rolled in opposite directions. As a means of illustration, I have chosen to reduce a square bar 7 to an oval 55

8 in stand 1, and in stand 2 the oval is reduced to a round 9, the rolls may, however, have any other shaped passes as desired. The oval or bar as it comes from stand 1 is positioned with its 5 major axis in a horizontal position, but upon entering the guide twister 10 the bar is turned about its axis so that by the time it has passed through the repeater 11 and reaches the guide 12 its end will have been turned substantially 90° 10 for entering the pass of rolls 4. Intermediate the twister 10 and repeater 11 is a guide 13, and intermediate the repeater and guide 12 is another guide 14.

The guide twister 10 as shown in Figs. 3 and 4 15 comprises a rotatable holder 15 which is cylindrical in shape with a flange 16 for holding it in position. The holder is provided with a rectangular opening 17 for receiving the split guides 18 which are of ordinary construction. The 20 guides are provided with straight grooved channels and are flared at their receiving ends so as to provide an entry for the bar as it comes from the rolls. The guides are secured in holder 15 by means of set bolts 19. The bearing for mounting 25 the holder is in the form of a pillow block having a base 20 and cap 21. The bearing is provided with a tongue 22 on its under side which is adapted to slide in a slot 23 of the supporting bracket 24 so that the bearing can be adjusted 30 horizontally. Attached to the guide holder 15 is a lever 25 for rotating the holder and the guides.

The entry guide 12 for pass 6 is mounted between the housings of stand 2 by means of rest 35 bars in the usual manner. This guide is mounted in a hollow rectangular guide box 26 in which are positioned stationary and movable guides 27 and 28 respectively, each having a longitudinally grooved inner face adapted to form a guiding 40 aperture for the bar. The stationary guide 27 is secured within the box 26 by means of one or more set bolts 29 while the movable guide 28 is adapted to be moved laterally toward the stationary guide by means of a pivoted lever 30 and screw 31 which is threaded into the side of the 45 box 26. The screw has a socket formed therein for the reception of a squared end of a shaft 32, which extends outwardly through the roll housing, thus providing a connection for the end of 50 the shaft. Thus, when shaft 32 is rotated in one direction the guide 28 is free to open relative to guide 27 and when the shaft is rotated in the opposite direction, guide 28 closes in on guide 27.

The guides 10 and 12 are operatively connected 55 for simultaneous adjustment by means of a lever 33 secured to the end of shaft 32. This lever is connected to lever 34 by means of link 35, and lever 34 in turn is connected to the cross shaft 36. Near the end of the shaft is attached a lever 60 37 which is connected to a bell crank 38 by means of rods 39 and 40, and turnbuckle 41. Lever 25 which is attached to the twister is connected to the bell crank 38 by means of the turnbuckle 42. It will be noted that levers 33, 34, 37, 65 and 38 are provided with additional holes for adjustment purposes so that the relative movement of the two guides may be varied to suit any condition. The turnbuckles 41 and 42 also provide for fine adjustment without stopping the rolling operation.

At the end of shaft 36 are mounted two discs 43 spaced apart, and in this space is mounted a lever 44 pivotally connected to the discs. The other end of the lever 44 is pivoted to supporting brackets 45. A solenoid magnet 46 is provided

for rotating the shaft 36 in one direction while a weight 48 will cause the rotation of the shaft in an opposite direction. The core 47 of the solenoid and weight are connected to lever 44 by means of rods 48 and turnbuckle 50 as shown in Fig. 2. 5 The solenoid is energized by means of an electric generator 51. Fig. 1 illustrates the wiring or circuit connections between the solenoid and generator which includes a flag switch 52 for opening and closing the circuit. The switch comprises 10 a flag 53 positioned in the guide 14 just ahead of guide 12. The flag is connected to a contactor 54 for completing the circuit in wires 55 and 56. The switch as a whole may be mounted in any 15 suitable manner but it should be mounted so that it may be moved toward or away from stand 2. The switch is opened by the movement of the bar being rolled as it passes under the flag 53, and after the bar has passed the switch the spring 57 will return the switch to its closed position as shown in Fig. 7. In place of the flag switch, an electric-eye or photo-cell may be used to advantage as a controlling means for opening and closing the circuit between the generator and solenoid. The operation of the eye would be effected by the passing of the bar under the eye. The eye in this case would be considered an equivalent to the flag switch, and as its purpose and function is well understood further description is considered unnecessary. 25

The curved repeater trough 11 is adapted to receive the bar after it issues from pass 5 and guides it in a curved direction to pass 6. The top of the trough is open to allow the rod or bar to be raised out of the trough by means of the kicker 35 58 and to extend over a table 59 in case the rod is delivered from pass 5 faster than is taken in by pass 6 thereby producing a loop or overfeed. The kicker is connected to shaft 36 which operates the guides and is automatically actuated by the 40 passing of the bar under the flag 53. A kicker of this type is shown in U. S. Patent 1,046,950.

In operation the normal position of the twister 10 is set so that when a bar issuing from pass 5 enters the guides 18 a twist is imparted to the 45 bar. This twist being only sufficient to turn the end of the bar about 90° by the time it has reached the guide 12. Normally the screw 31 is in a retracted position which allows guide block 28 to open relative to guide block 27. This 50 provides for the free entry of the end of the bar into the guide. Under these conditions the flag switch is in the closed position as shown in Fig. 7 which closes the electrical circuit in wires 55 and 56. When the circuit is closed the solenoid is 55 energized which lifts the core of the magnet. In other words, with the switch closed the solenoid is energized, the guide twister 10 is in its twisting position, and the guide 12 is open. When the end of the bar being rolled reaches the flag 53 the 60 switch is opened, thus de-energizing the solenoid and allowing the weight 48 to rotate shaft 36 in a reverse direction so as to close the entry guide 12 on the bar and simultaneously turn the twister to a position coincident with pass 5 as shown in 65 Fig. 4. This feature of automatically turning back the twister, after the bar has entered guide 12, permits the bar to emerge from pass 5 in an untwisted position, thereby releasing the torsion on the rod. The position of the switch relative 70 to pass 6 is determined by trial, and it is important that the switch be placed so that after the switch is opened by the passing bar, the end of the bar will have entered the guides and about reached the bite of the roll pass before the entry 75

guides close upon the bar. If the entry guides close too quickly it may retard or stop the movement of the bar. The lapse of time between the opening of the switch and the entry of the 5 bar into the bite of the rolls is caused by the inertia and friction in the operating parts. However, with the rod moving at a high rate of speed, this time interval is very short.

It will be noted that the solenoid sets the twister 10 and the entry guide in one position only, and that the weight 48, which is an independent source of power, closes the entry guide and returns the twister to its untwisted position.

The operating mechanism of the twister is constructed 15 so that the angle of the twister can be increased or diminished, and the amount of release throw varied to suit the roller in a few seconds and without delaying the on-coming bar.

The advantages offered by this invention will 20 be apparent to those skilled in the art. By turning and controlling the bar it will be delivered to the entry guides of the second pass uniformly and in proper position to receive the shaping and reducing work of the pass; the releasing of 25 the torsion on the bar exerted by the twister, because if the twister remains set in its former position this torsion is communicated to the entry guides of the second pass, the strain constantly increasing on both twister and entry 30 guides as long as the bar is in both and the loop is increasing in length; reduction of wear on the twister and entry guides; and the elimination of the tendency to scratch the bar. In rolling very long bars with a fixed twister the accumulating 35 torsion is sometimes sufficient to cause the looped portion of the bar to rise up and twist, with obvious serious results both to the operators of the mill and the mill itself—this danger is also eliminated. The tendency of a growing twist in 40 a bar to push the rolls in opposite directions is relieved, thereby producing a more uniform section and less end thrust on the roll bearings.

While we have illustrated and described one particular embodiment of our invention, it will 45 be understood that in its broader aspects, the invention is not limited to the specific means shown covering the various movements and actions described, producing the results stated.

Having thus described our invention, what we 50 claim as new and desire to secure by Letters Patent, is:

1. In a rolling mill the combination with two roll passes, of a straight grooved guide rotatably mounted at the delivery side of the first pass and 55 positioned to impart twist to the piece being rolled as it emerges from said pass, a separable guide located at the entry side of the second pass, and actuating means operatively connecting said guides for simultaneously closing said separable 60 guide and turning said straight grooved guide to an untwisting position so as to relieve its twisting effect on the piece when in engagement with both guides.

2. In a rolling mill the combination with a plurality of roll passes, of a rotatable guide at the delivery side of one pass and positioned to twist the piece being rolled as it emerges from said pass, a guide having a fixed plate and a movable plate positioned at the entry side of another 65 pass, and means for simultaneously adjusting said movable plate and turning said rotatable guide to an untwisting position so as to relieve its twisting effect on the piece.

3. In a rolling mill the combination with two roll passes, of a rotatable guide at the delivery 70

side of the first pass and positioned to twist the piece being rolled as it emerges from said pass, a separable guide adapted to be opened or closed at the entry side of the second pass, a repeater for conducting the piece from the first pass to 5 the second pass, and means for simultaneously closing said separable guide upon the entry of the piece to the second pass and to turn said rotatable guide so as to allow the piece to continue its movement from the first stand in an untwisted 10 position.

4. In a rolling mill the combination with two stands of rolls provided with grooved passes requiring the turning of the bar being rolled between the stands, of a curved repeater for conducting the bar from one to the other stand, a rotatably mounted twister guide having a straight opening positioned at the delivery side of the first stand, a separable guide at the entry side 15 of the second stand, and means operatively connecting both of said guides for simultaneously opening or closing said separable guide and rotating said twister guide.

5. In a rolling mill, a set of rolls provided with an elongated pass, a second set of rolls having a 20 pass differing from the first pass, means for conducting the bar being rolled from one to the other pass, a rotatably mounted twisting guide having straight grooves positioned between said conducting means and the first set of rolls, a separable 25 guide between said conducting means and said second set of rolls, and means for simultaneously closing said separable guide against the bar entering the pass of said second set of rolls and to rotate said twisting guide.

6. In a rolling mill the combination with two roll passes, of a rotatable guide positioned at the delivery side of the first pass, a separable guide adapted to be opened and closed positioned at the entry side of the second pass, a repeater extending from the delivery side of said rotatable guide to the entry side of said separable guide, said rotatable guide being positioned to receive and twist the piece being rolled as it emerges from the first pass and to deliver the piece to said separable 45 guide by means of said repeater, said separable guide being in its open position relative to the twisted position of said rotatable guide when receiving the end of the piece, means operatively connecting said guides for simultaneously closing 50 said separable guide upon the piece being rolled and for returning the rotatable guide to its untwisted position so as to relieve the torsion in the piece and its wedging effect upon the rolls.

7. In a bar rolling mill the combination with two roll passes, of a stationary guide rotatably mounted at the delivery side of the first pass, stationary guides intermediate said passes for conducting the bar from the delivery side of the first pass to the entry side of the second pass, said rotatable 60 guide being positioned relative to the first roll pass so as to engage and immediately twist the bar upon entering the guide and to present the bar to the second roll pass by means of said intermediate guides, and automatically operated 65 means controlled by the movement of the bar as it approaches said second pass for turning said rotatable guide whereby it is repositioned so as to coincide with the first pass thereby relieving the twist in the bar as it passes through said 70 guide.

8. The combination with a pair of rolling units, of a repeater through which a bar emerging from one unit is directed to the pass of the other unit, a twister interposed between the first rolling unit 75

and the repeater through which a rod emerging from the first rolling unit must pass and by means of which the rod is turned the necessary amount to be received by the pass of the second unit, a 5 separable guide between said repeater said second unit, means for closing said separable guide against the bar entering the pass of said second unit and for simultaneously turning said twister so as to relieve the torsion in the bar as it emerges 10 from said first rolling unit.

9. In a rolling mill, the combination with two stands of roll passes, a guide twister at the delivery side of the first pass, a separable guide at the entry side of the second pass, means for simultaneously adjusting said separable guide and turning said twister, and means for regulating the angular position of said twister relative to its corresponding roll pass.

10. In a rolling mill, the combination with two 20 stands of rolls, a guide twister at the delivery side of the first stand, a separable guide at the entry side of the second stand, means for simultaneously opening said separable guide and turning said twister in one direction to twist the piece 25 being rolled, and means independent of said first means for automatically closing said separable guide and turning said twister in the opposite direction to untwist the piece after it has entered the separable guide.

30 11. In a rolling mill, the combination with two stands of rolls, a guide twister at the delivery side of the first stand, a separable guide including a fixed guide plate and a movable guide plate at the entry side of the second stand, electrically operated means controlled by a travelling bar being rolled for releasing said movable guide and simultaneously turning said twister in one direction, and means independent of said electric means for closing said movable guide and turning said 40 twister in the opposite direction.

12. In a rolling mill, the combination of two stands of rolls, a guide twister at the delivery side of the first stand, a guide box secured to the housings of the second stand, a fixed guide 45 plate and a movable guide plate mounted in said box, means controlled by the bar being rolled to release or close said movable plate and to rotate said twister in opposite directions, a repeater between said twister and said guide box, and means for adjusting the degree of rotation 50 of said twister.

13. In a rolling mill, the combination with two stands of roll passes, of a guide twister in fixed 55 relation to the delivery side of the first pass, a normally energized power member for positioning said twister so as to twist the piece being rolled as it emerges from said pass, a stationary repeater for conducting the piece from the twister to the second pass, entry guides for the second pass, control means adjacent the entry side of said second pass operable by the piece being rolled as it approaches the second pass for automatically de-energizing said power member, and means independent of said power member for turning said twister to relieve the twist in said 60 65

piece after its forward end has reached the second pass and while still in engagement with the piece.

14. In a rolling mill, the combination with two stands of rolls having different passes, an entry 5 guide box secured to the housings of the second stand, a fixed guide plate and a movable guide plate each having a grooved inner face mounted in the guide box, a screw threaded into the side of the guide box, a shaft connected to the screw, 10 a guide twister at the delivery side of the first stand carrying straight grooved guides, means operatively connecting said screw shaft with said twister, electrically operated means controlled by the bar being rolled adapted to rotate 15 said shaft and screw to release the movable guide plate from the fixed guide plate and rotate said twister so as to twist a bar emerging from the first stand of rolls, and means independent of the electrically operated means for rotating 20 the shaft and screw in the reverse direction to that of the electrically operated means for moving the movable guide plate toward the fixed guide plate and to rotate said twister in the reverse direction so as to untwist the bar but not 25 until its forward end has entered the entry guide.

15. In a rolling mill, the combination with two stands of rolls having differently shaped passes, of a twister carrying a guide positioned at the delivery side of the first pass, an opening and 30 closing guide positioned at the entry side of the second pass, a repeater between said guides, a power operated member operably connected to said guides for opening said second guide and simultaneously turning said twister for positioning the guide carried thereby at an angle to said first pass so as to twist the bar as it emerges 35 from said pass, power control means adjacent said second guide actuated by the bar as it approaches the second pass for automatically 40 interrupting the power to said member, and means independent of said power member for automatically closing said second guide and simultaneously returning said twister to a position 45 so as to allow the piece to continue its movement from the first pass in an untwisted position and thereby relieve its torsional strain on the guides and wedging effect on the rolls.

16. In a rolling mill, the combination with two stands of rolls, of a rotatable guide twister 50 mounted in fixed relation to the delivery side of the first stand of rolls, fixed guides for directing the bar being rolled from said twister to the second stand of rolls, actuating means for rotating said twister, twister control means positioned in the way of said fixed guides and in front of said second stand of rolls, and means operatively connecting said control with said actuating means, said control being directly responsive to the effect of a bar passing through 55 60 said fixed guides for automatically rotating said twister.

WILLIAM H. CATTERALL.
WILLIAM J. BARRY.
